SHEET-RETARDING DELIVERY FOR PRINTING-MACHINES.

1,085,665.

Specification of Letters Patent.

Patented Feb. 3, 1914.

Application filed February 10, 1913. Serial No. 747,377.

To all whom it may concern:

Be it known that I, ERNEST O. CARTWRIGHT, residing at Springfield, in the county of Clark and State of Ohio, have 5 invented a new and Improved Sheet-Retarding Delivery for Printing-Machines, of which the following is a specification.

The object of my present invention is to provide means for retarding the travel of a 10 printed sheet of paper in a printing machine as it passes to the point of delivery and is deposited upon other previously printed sheets, and in such a manner as to lengthen the time of exposure to the air, 15 of each sheet, between the movements of printing and delivery, in order that the ink deposited upon the sheet may have opportunity to "set" or sufficiently dry to avoid "off setting" or soiling the sheet that is 20 delivered on top of it.

It is well known that printed sheets from presses, especially those of rapid operation, when delivered in the ordinary manner, are often soiled on their under side by contact 25 with the freshly printed sheets next below them.

Among devices now used in this art for overcoming the objection noted, is a means requiring three complete printing performances of the press before a sheet printed at the first impulse comes to rest upon the delivery pile, and such means includes a special construction of tape rollers and tapes in a telescoping frame. Such means is more 35 especially adapted for large and relatively slow running presses. Other devices for the purpose are employed that deliver sheets alternately to different piles, while other means are being used, in the nature of a 40 traveling conveyer or apron to receive the sheets as they are printed for carrying them some distance in the air before piling them up. The latter method is objectionable, in that it requires more space than can be well 45 afforded for the purpose and for that reason has not come into use extensively.

My sheet retarding delivery mechanism can be attached, with reasonable convenience, to any printing press of the "front 50 delivery" type, but it is more especially designed for and is preferably embodied to form a coöperative part of the complete construction of my rapidly operated cylinder job printing press fully disclosed in my

copending application, filed on even date 55 with this application, Serial No. 747,375 in which application the general construction, the operation, and the advantages of my present invention are set forth.

In its generic nature my present invention involves means for intermittently arresting the dropping of the printed sheets, and finally depositing the said printed sheets, repeating the arresting function as many times as may be necessary or desired 60 before the sheet is finally allowed to rest on the printed pile.

In its more subordinate features my invention embodies the novel arrangement and peculiar combinations of the parts herein- 65 after fully explained, specifically pointed out in the appended claims and illustrated in the accompanying drawings, in which:

Figure 1 is a perspective view of my sheet retarding and delivery mechanism, the 75 hinged end of the delivery tape holder being shown swung up, to the better illustrate the operative connections of the "fliers" 80 hereinafter specifically set out. Fig. 2 is a diagrammatic longitudinal section of the mechanism shown in Fig. 1, the parts being 85 shown in their operative position and direction of movement of the sheet from the printing cylinder being indicated by arrows, the first, third and fifth sheet intercepting 90 "fliers" being shown at the inner or "pulled back" position, and the second, fourth and last sheet intercepting fliers shown at their outermost or sheet holding position. Fig. 95 3 is a view similar to Fig. 2, the positions of the two sets of sheet intercepting fliers being reversed to that shown in Fig. 2. Fig. 4 is a detail plan view, parts being in section, of one of the hinged bearing devices used for pivoting the delivery board, herein- 100 after explained. Fig. 5 is a detail perspective view that illustrates one of the crank drives for actuating one of the two sets of "fliers."

In the drawings I have illustrated only so much of my high speed press disclosed 105 in my copending application as is necessary to show the practical application of my present invention, and in the said drawings, 1—1 designate the delivery end of the opposite side frames of the printing press, 2 the printing cylinder, preferably arranged as shown in my press mechanism before referred to.

3 is the main offtake or endless tape carrier, that takes the printed sheet as it is delivered from the front of the cylinder and 4 designates the sheet discharging or delivery tape frame from which the printed sheets pass on to the retarding and delivering devices, the construction and the operation of which will be readily understood by reference to Fig. 1 of the drawings. The 10 said devices are designed for dropping, by gravity, a printed sheet and intercepting the same a plurality of times before it is finally deposited, whereby to increase, as it were, the time until the sheet is finally deposited without in the slightest retarding the printing operations and the offtake or delivery of the printed sheet from the cylinder.

To accomplish the result just stated in a 20 simple, efficient and positive manner I provide a series of toothed or pronged supporters, hereinafter termed "fliers," all horizontally disposed and in parallelism and for longitudinal reciprocation with respect to 25 the travel or delivery route of the printed sheet. These fliers I arrange in pairs, each pair comprising a set, consisting preferably of a plurality of fliers, three being shown as constituting each set. Each set of fliers includes a series of crossbars 5 that extend transversely of the delivery end of the machine. One set of the cross bars 5 are fixedly secured at one end to a traveling head 6 and slidably held and guided between the rails 7 30 that constitute a part of the side frames, the other set of crossbars 8 being likewise secured to and projected from a like traveling head 9—slidably mounted on the rails 10 of the opposite frame—as is clearly shown in 35 Fig. 1. Each of the bars 5—8 form the supporting means for the sheets and at the same time act as interceptors, since they intermittently hold and retard the delivery of the printed sheet after it is discharged from 40 the hinged delivery board 9.

The sheet supporters or "fliers" include a desired number of finger rods or prongs fastened into and at right angles to their respective cross or head bars from which they 50 extend in the horizontal plane, and each of the said prongs has its outer end curved upward to such extent as will not interfere with their clearance with the "flier" next above in the assembly of "fliers." The upward projecting of the prong ends also provides for giving the forward edge of the sheet an upward deflection as the "flier" is drawn under it—thereby lessening the likelihood of the sheet sagging at that point when the 55 front ends of the "flier" prongs are in vertical alinement in the progress of the stroke.

The several "fliers" are of like construction, and are relatively so mounted that in one sliding housing the "fliers" are mounted 60 higher up in relation to the guideways than

in the opposite housing, so that when the two housings are assembled in the machine, the "fliers" in one housing will clear between the "fliers" in the other housing in their horizontal travel. The longer dimension of 70 the "fliers" is such that the free ends of the ones on one side will clear the housing on the other side as they pass during the travel of the slides. The shorter dimension of the "fliers" is sufficiently greater than the dimension of the maximum sheet to be carried through to prevent the dropping of the front edge of the sheet, should the "fliers" stop or pause halfway of their stroke, as is liable to be the case with the promiscuous stopping of the printing mechanism with which the "fliers" coöperate. 75 80

11 designates a toothed or barred rake, the head 12 of which extends transversely of the machine, and is located at a point in front of the supporting bar of the "fliers" when the machine is at its maximum stroke forward, that is—on the side of the bar from which the prongs project, and the said rake 11 is fixedly suspended in a vertical plane, 90 and extended downward a sufficient distance to act as a guide for the rear edge of the sheets as they drop from one "flier" to the one beneath and also after it has left the lowermost "flier." 13 designates a second 95 toothed or barred rake and it includes a head in the nature of a crossbar 14, the ends of which are rockably mounted in bearing boxes 15 shiftably mounted on bracket arms 16 that are hingedly connected at their rear 100 ends on the side bars of the frame. The boxes 15 are adjustably held on the arms 16 by the clamp screws 17 and the crossbar 14 is held to its rocked adjustments by the screws 18. The prongs 19 on the front rake 105 act as guides for the front edge of the sheet as it is intermittently dropped and for the front edge of the pile of sheets, as shown.

At a proper point in the rear of the "flier" assembly, is a cross shaft 20 and it is 110 journaled in the side frame members 21 and adapted to receive motion from the printing cylinder by a chain 22 that takes over a sprocket 23 on the cylinder shaft, a sprocket 24 on the shaft 20 and over an idler 25 as 115 shown, it being obvious that as the printing cylinder is oscillated through the connections with the form bed the shaft 20 is oscillated—moved a half revolution—in each complete printing movement of the press. 120 Each end of the cross shaft 20 carries a crank 26 of a proper eccentricity to accomplish the full movement of the "fliers." The cranks 26 are set diametrically opposite each other, and each is pivotally joined with a connecting rod 27—which rods also pivotally join 125 with the sliding housings on their corresponding sides of the machine. A removable bearing 28 is mounted in each of the upper end frame members, and the said 130

bearing 28 receives the hollow sleeves 29—as is best shown in Fig. 4, which constitute one terminal of the supporting frame of the delivery tapes 4 that extends from the pivotal point to the point in the delivery where the “fliers” come to pause at the forward end of the stroke.

31 designate the terminals of the opposite ends of the delivery tape frame that receives the printed sheet from the press, the said terminal 31 being pivotally mounted on the hollow sleeve 29, see Fig. 4. A shaft 32 journals in the hollow sleeves 29 and it carries the main tape driving roll 33 of the sheet delivery and is adapted to receive a continuously rotary motion through the crossed belt 34 that takes over the drive pulley 35 on the main drive shaft of the press.

On that end of the delivery device onto 20 which the printed sheet is delivered from the printing cylinder, is mounted a freely revoluble tape roller 36 connected by the endless tapes 37 with and driven by the main tape roller 33. At the forward end 25 of the delivery device, at the pausing point of the “fliers” is suitably mounted another freely revoluble tape roller 38 that is connected, by the endless tapes 39, and is rotated by the main tape roller 33.

30 By reason of supporting the first and second delivery tape frames in the manner described and shown, provides, as it were, a ready removable conveyer, since both tape frames can be swung up and readily sustained at their elevated positions, thereby providing for easy access to the press mechanism, with a minimum expense of time and energy, it being also apparent that by hinging the delivery tape frames and driving 35 the tape rollers from a central point, the mechanism can be folded up at once without disturbing the adjustments or position of the parts.

The operation of the delivery and the retarding means is best explained as follows: 40 The tape roller 33 is given proper speed to time the travel of the sheet from the printing cylinder to the top most of the “fliers” in order that each time a “flier” is moved 45 to a receiving position there will be a sheet to come upon it. At each complete performance of the press the “fliers” make a complete reciprocation, that is—the topmost “flier” and the companion “fliers” of the 50 set including the topmost “flier” change places with the several “fliers” that constitute the other set of “fliers” and then restored to the original position. As before 55 stated, the front ends of the teeth or prongs of the “fliers” are free, and the ends of the “fliers” opposite the housing in which they are fastened are free, and the rakes or barred members are adjusted for the proper width of sheet going through. At 60 the point where the printing cylinder pre-

sents a sheet to the delivery tapes, the forwarding motion of the latter advances the sheet and propels it into space above the topmost “flier” with the front edge of the sheet against the forward rake or barred member, and the rear edge of the sheet near the rear rake or barred member. The topmost “flier” is drawn from under the sheet at the time the “flier” next below is projected under it, and at the next operation 70 of the press the top flier is presented to receive the printed sheet, while the previous sheet is dropped to the “flier” No. 3. At the next operation, by repetition, the first sheet drops to No. 4—the second to No. 3, 75 and the third to the topmost “flier.” It is understood I do not limit myself to any specific number of “fliers” as it will be seen each pair of “fliers” suffices to retard the 80 progress of the sheet through one complete performance of the press, and it is a matter of choice how many pairs are to be used. To properly support the sheet in the delivery, and present the topmost “flier” to receive each sheet as it comes from the 85 press, the fliers, which I designate as *a—b—c* are employed, and the action of the sheet in regard to them is the same as in regard to the others, except that it occurs at the opposite reciprocation from that of the other 90 “fliers.”

The object in having the forward rake or barred member hinged in the manner explained is to permit the sheets to be easily removed from the delivery pile by raising 100 the rake out of the way, and by having it pivotally suspended, it still acts as a guide for the forward edge of the sheets between the “fliers,” even if lifted sufficiently to uncover the front edge of the delivery pile. 105

From the foregoing taken in connection with the accompanying drawings, the complete construction, the operation and the advantages of my invention will be readily apparent to those skilled in the art to which 110 my invention relates.

While the specific arrangement of parts shown presents a practical arrangement of my invention—the details may be varied or modified to suit the particular requirements 115 for which my said invention may be utilized.

While the specific arrangement of the parts shown and described discloses a practical arrangement of my invention, it is obvious, that under the scope of the appended 120 claims the said details of construction may be materially modified or varied without departing from my invention. For example, I have described and shown the means for actuating the “flier” assembly as actuated 125 directly from the printing cylinder shaft.

When my retarding and separating mechanism is used in connection with a “two revolution” printing machine, it would be impossible to effect the desired operation of 130

the said mechanism by gearing up the said mechanism directly with the printing cylinder, hence in the practical application of my invention the source of driving power for the said mechanism may be any suitable shaft on the served machine.

What I claim is:

5. In a sheet delivering mechanism for printing machines, which includes a conveyor that discharges the printed sheet to cause it to drop by gravity onto a previously deposited printed sheet; devices of relatively fixed dimensions for intercepting and temporarily holding the said printed sheet as it 10 gravitates to rest on the preceding printed sheet or sheets.
10. In a sheet delivering mechanism for printing machines in which is included sheet discharging devices that drop the sheet flatwise over the sheet pile receiver; devices of relatively fixed dimensions for intermittently intercepting the printed sheet after it leaves the discharging devices, said means being operatively connected with and actuated by the sheet printing mechanism.
20. In a sheet delivery for printing machines; which includes devices for discharging the printed sheet to fall flatwise upon a prior deposited printed sheet; devices of relatively fixed dimensions for retarding the drop of the said sheet and temporarily holding it before it falls onto the prior printed sheet.
30. In a sheet delivery for printing machines that includes devices for discharging the printed sheet flatwise upon a prior deposited sheet; catcher fingers for retarding the fall of the said sheet and temporarily sustaining it while a subsequent sheet is 35 passing to its point of discharge.
40. In a sheet delivery for printing machines, in which is included a continuously moving sheet carrier that discharges the sheet flatwise at a point above the sheet pile receiver; means for retarding the drop of the sheet, said means comprising at least one reciprocatory member of relatively fixed dimensions that moves under the falling sheet and devices for confining the sheet within a 45 predetermined path of dropping movement when the said member moves from under the sheet.
50. In a sheet delivery for printing machines, in which is included a continuously moving sheet carrier that discharges the printed sheet flatwise at a point over the sheet pile receiver; means for retarding the drop of the discharged sheet, said means including a plurality of reciprocatably mounted fingers disposed in different horizontal planes movable across the path of the falling sheets and means for confining the sheets within a predetermined path of dropping movement as the said fingers move under the said sheets.
55. In a sheet delivery for printing machines, in which is included a continuously moving sheet carrier that discharges the printed sheet flatwise at a point over the sheet pile receiver; means for retarding the drop of the discharged sheet, said means including a plurality of sets of reciprocatably mounted catcher fingers disposed in different horizontal planes movable across the path of the falling sheets and means for confining the sheets within a predetermined path of dropping movement as the said fingers move under the said sheets.
60. In a sheet delivery for printing machines, in which is included a continuously moving sheet carrier that discharges the printed sheet flatwise at a point over the sheet pile receiver; means for retarding the drop of the discharged sheet, said means including a plurality of sets of reciprocatably mounted catcher fingers disposed in different horizontal planes movable across the path of the falling sheets and means for confining the sheets within a predetermined path of dropping movement as the said fingers move under the said sheets.
65. In a sheet delivery for printing machines, in which is included a continuously moving sheet carrier that discharges the printed sheet flatwise at a point over the sheet pile receiver; means for retarding the drop of the discharged sheet, said means including a plurality of sets of reciprocatably mounted catcher fingers disposed in different horizontal planes movable across the path of the falling sheets and means for confining the sheets within a predetermined path of dropping movement as the said fingers move under the said sheets.
70. In a sheet delivery for printing machines, in which is included a continuously moving sheet carrier that discharges the printed sheet flatwise at a point over the sheet pile receiver; means for retarding the drop of the discharged sheet, said means including a plurality of sets of reciprocatably mounted catcher fingers disposed in different horizontal planes movable across the path of the falling sheets and means for confining the sheets within a predetermined path of dropping movement as the said fingers move under the said sheets, and a means operable from the printing cylinder drive that actuates the fingers.
75. In a sheet delivery for printing machines; a means for conveying the printed sheet to the point of discharge and dropping it, and a set of reciprocating catcher members each of relatively fixed dimensions for intermittently retarding the drop of the sheet as it falls to rest on a preceding sheet.
80. In a sheet delivery for printing machines; a means for conveying the printed sheet to the point of discharge and dropping it, and a set of reciprocating catcher members each of relatively fixed dimensions for intermittently retarding the drop of the sheet as it falls to rest on a preceding sheet.
85. In a sheet delivery for printing machines; a means for conveying the printed sheet to the point of discharge and dropping it, and a set of reciprocating catcher members each of relatively fixed dimensions for intermittently retarding the drop of the sheet as it falls to rest on a preceding sheet, and other means for holding the sheet within predetermined confines as it intermittently lowers onto the pile of printed sheets.
90. In a sheet delivery for printing machines, comprising the following elements in combination: means for conveying the sheet and dropping it flatwise at the point of delivery, a plurality of horizontally disposed catcher frames, onto which the sheet is successively dropped from the upper one to the next lower one of the same frames, means for reciprocatably moving each pair of catcher frames relatively in reverse directions and other means for holding the sheet within prescribed confines as it drops from one catcher frame to another catcher frame.
95. In a sheet delivery mechanism for printing machines of the front delivery type—means for conveying the sheet and dropping it flatwise at the point of delivery—said means including a delivery board from which the printed sheets are dropped flatwise, a horizontally disposed reciprocatory catcher frame of relatively fixed dimensions that receives the dropped sheet and temporarily arrests its fall onto the printed sheet pile, and other means for keeping the sheet within predetermined confines as it leaves the catcher frame.
100. In a sheet delivery mechanism for printing machines of the front delivery type; means for conveying the sheet and dropping it flatwise at the point of delivery, said means including a delivery board and a continuously operable endless tape carrier mounted on the board, the said board being
105. In a sheet delivery mechanism for printing machines of the front delivery type; means for conveying the sheet and dropping it flatwise at the point of delivery, said means including a delivery board and a continuously operable endless tape carrier mounted on the board, the said board being
110. In a sheet delivery mechanism for printing machines of the front delivery type; means for conveying the sheet and dropping it flatwise at the point of delivery, said means including a delivery board and a continuously operable endless tape carrier mounted on the board, the said board being
115. In a sheet delivery mechanism for printing machines of the front delivery type; means for conveying the sheet and dropping it flatwise at the point of delivery, said means including a delivery board and a continuously operable endless tape carrier mounted on the board, the said board being
120. In a sheet delivery mechanism for printing machines of the front delivery type; means for conveying the sheet and dropping it flatwise at the point of delivery, said means including a delivery board and a continuously operable endless tape carrier mounted on the board, the said board being
125. In a sheet delivery mechanism for printing machines of the front delivery type; means for conveying the sheet and dropping it flatwise at the point of delivery, said means including a delivery board and a continuously operable endless tape carrier mounted on the board, the said board being

- hinged to swing up without affecting the running of the endless tape carrier, a "flier" that receives the sheet and temporarily retards its fall onto the sheet pile, said "flier" 5 consisting of a toothed pronged crossbar longitudinally reciprocable with respect to the delivery route of the printed sheet and over the sheet pile receiver and other means for keeping the sheet within predetermined 10 confines as the "flier" moves from under it.
13. A sheet retarding delivery mechanism for printing machines, comprising the following elements in combination; a means for conveying the sheet to the point of discharge and dropping it, sheet supporters 15 consisting of crossheads having forwardly extended prongs—said supporters being arranged in pairs, means for reciprocatably moving the sheet supporters and each pair 20 in reverse direction to the other, and means for holding the sheet in predetermined confines as it drops from one supporter to the next lower supporter.
14. A sheet retarding delivery mechanism 25 for printing machines, comprising the following elements in combination; a means for conveying the sheet to the point of discharge and dropping it, sheet supporters consisting of crossheads having forwardly 30 extended prongs—said supporters being arranged in pairs, means for reciprocatably moving the sheet supporters and each pair in reverse direction to the other, and means for holding the sheet in predetermined 35 confines as it drops from one supporter to the next lower supporter, the last said means comprising barred rakes vertically disposed with respect to the sheet supporters, and arranged to form the opposite sides of a sheet 40 pile confining space.
15. A sheet retarding delivery mechanism for printing machines, comprising the following elements in combination; a means for conveying the sheet to the point of discharge and dropping it, sheet supporters 45 consisting of crossheads having forwardly extended prongs—said supporters being arranged in pairs, means for reciprocatably moving the sheet supporters and each pair 50 in reverse direction to the other, and means for holding the sheet in predetermined con-
- fines as it drops from one supporter to the next lower supporter, the last said means comprising an inner barred rake and an outer barred rake, vertically disposed with respect to the sheet supporters, said barred rakes forming the opposite sides of a sheet 55 confining space, the outer barred rake being adjustably mounted for regulating the width of the said space. 60
16. A sheet retarding delivery mechanism for printing machines, comprising the following elements in combination; a means for conveying the sheet to the point of discharge and dropping it, sheet supporters 65 consisting of crossheads having forwardly extended prongs—said supporters being arranged in pairs, means for reciprocatably moving the sheet supporters and each pair in reverse direction to the other, and means 70 for holding the sheet in predetermined confines as it drops from one supporter to the next lower supporter, the last said means comprising an inner barred rake and an outer barred rake, vertically disposed with 75 respect to the sheet supporters, said barred rakes forming the opposite sides of a sheet confining space, the outer barred rake being adjustably mounted for regulating the width of the said space, and a support for the said 80 outer barred rake hingedly connected to the framing.
17. A sheet retarding delivery mechanism for end delivery printing machines having reversely rotatable printing cylinders, and a 85 conveyer that carries the printed sheet to the point of delivery and discharges it flatwise onto the printed sheet pile receiver; a series of sheet intercepting frames, reciprocatably movable in parallelism with the moving 90 sheet—said frames being arranged in pairs and each including a sliding frame, a drive shaft having oppositely projected cranks, one at each end—a link connecting each crank with the sliding frame at its corresponding side and a drive connecting the 95 crank shaft and a suitable shaft on the served machine.
